UNITED STATES PATENT OFFICE.

JOHN W. McCANN, OF PAULS VALLEY, OKLAHOMA.

FILE.

1,395,197.

Specification of Letters Patent. Patented Oct. 25, 1921.

Application filed June 19, 1920. Serial No. 390,186.

To all whom it may concern:

Be it known that I, JOHN W. McCANN, a citizen of the United States, residing at Pauls Valley, in the county of Garvin and

5 State of Oklahoma, have invented certain new and useful Improvements in Files, of which the following is a specification, reference being had to the accompanying drawings.

10 This invention relates to certain improvements in files and has relation more particularly to a device of this general character especially designed and adapted for use in connection with bills or the like and it is an 15 object of the invention to provide a novel and improved file of this general character having means whereby papers may be filed in accordance with months of the year or other classifications.

20 The invention consists in the details of construction and in the combination and arrangement of the several parts of my improved file whereby certain important advantages are attained and the device rendered 25 simpler, less expensive and otherwise more convenient and advantageous for use, as will be hereinafter more fully set forth.

The novel features of my invention will hereinafter be definitely claimed.

30 In order that my invention may be the better understood I will now proceed to describe the same with reference to the accompanying drawings, wherein:

Figure 1 is a view in top plan illustrating a file constructed in accordance with an embodiment of my invention, with a portion broken away;

Fig. 2 is a fragmentary view in bottom plan of my improved file illustrating certain features of the connection of a hook member with the body or plate; and

Fig. 3 is a sectional view taken substantially on the line 3—3 of Fig. 2.

As disclosed in the accompanying drawings B denotes a body of suitable material in the form of a sheet or plate preferably rectangular in form and the marginal portions of said body are returned or doubled as indicated at 1 so that said marginal portions

50 will possess increased strength to facilitate the mounting of the filing hooks or members F.

Each of the filing members or hooks F as herein disclosed is formed of a single 55 length of material and has one end portion disposed through the body B inwardly of

and in close proximity to the returned or doubled portion 1 with the extremity clamped against the under face of the body. The wire is then extended as indicated at 2 60 across the returned or doubled portion 1 and bent to bridge the marginal portion of the body and extended inwardly of the body as indicated at 3. The wire is then directed through the body B and formed into a loop 65 4 underlying the portion 2 and extending between the body B and the returned or doubled portion 1. The wire is then extended upwardly to afford the hook 5 with which the bills or other papers are adapted to be 70 engaged.

In practice it is preferred that twelve file members or hooks be employed with each of said hooks identified by a month of the year, and it is desired that the upper face 75 of the body B immediately adjacent each of said members or hooks F be provided with a calendar 6 of one of the months of the year so that the filing of bills or other papers may be arranged in accordance with the 80 month in which they may have been received, or as other occasions of practice may require.

The central field of the body B may have arranged thereon any fanciful matter 85 desired, such as advertising matter or the like.

If desired clamps may be employed in lieu of the members or hooks F.

From the foregoing description, it is thought to be obvious that a file constructed 90 in accordance with my invention is particularly well adapted for use by reason of the convenience and facility with which it may be assembled and operated and it will also be obvious that my invention is susceptible 95 of some change and modification without departing from the principles and spirit thereof and for this reason I do not wish to be understood as limiting myself to the precise arrangement and formation of the several 100 parts herein shown in carrying out my invention in practice except as hereinafter claimed.

I claim:

1. A file comprising, in combination, a 105 body and a holding member carried thereby, said holding member being formed of a single length of material and having an end portion disposed through the body and extended outwardly over the face of the body 110 to the margin thereof and then returned over the opposite face and extending through

- the body, said strand being then formed into a loop engaging the first face of the body, said strand being extended from the loop to afford a receiving hook.
- 5 2. A file comprising, in combination, a body and a holding member carried thereby, said holding member being formed of a single length of material and having an end portion disposed through the body and extended outwardly over the face of the body to the margin thereof and then returned over the opposite face and extending through the body, said strand being then formed

into a loop engaging the first face of the body, said strand being extended from the loop to afford a receiving hook, the margin of the body being folded over with the loop extending between the body and the folded portion.

In testimony whereof I hereunto affix my signature in the presence of two witnesses.

JOHN W. McCANN.

Witnesses:

E. WESTBROOK,
HARRY OLIPHINT.
